UNITED STATES PATENT OFFICE

161,662

THICKNESS GAUGE

William C. Stratman, Los Angeles, Calif., assignor
to North American Aviation, Inc.

Application July 22, 1950, Serial No. 11,319

Term of patent 14 years

(Cl. D52—1)

To all whom it may concern:

Be it known that I, William C. Stratman, a citizen of the United States, residing at Los Angeles, in the county of Los Angeles and State of California, have invented a new, original, and ornamental Design for a Thickness Gage, reference being had to the accompanying drawings, forming part thereof.

Fig. 1 is a perspective view of a gage, showing my new design.

Fig. 2 is a top plan view of the gage.

Fig. 3 is a side elevational view of the gage.

Fig. 4 is an end elevational view of the gage taken from the right as shown in Fig. 3.

Fig. 5 is an end elevational view of the gage taken from the left as shown in Fig. 3.

I claim:

The ornamental design for a thickness gage, substantially as shown.

WILLIAM C. STRATMAN.
